(57) **CLAIM**

I claim the ornamental design for combined tub filler and overflow assembly, as shown and described.

DESCRIPTION

FIG. 1 is a front, top and left side isometric view of the combined tub filler and overflow assembly showing my new design;

FIG. 2 is a front view thereof;

FIG. 3 is a top view thereof;

FIG. 4 is a left side view thereof; and,

FIG. 5 is a bottom view thereof.

The left and right sides thereof are mirror images of one another.
